UNITED STATES PATENT OFFICE.

JOHN ERLE DOUGLAS, OF BIRMINGHAM, ALABAMA, ASSIGNOR TO AMERICAN CASTING COMPANY, OF BIRMINGHAM, ALABAMA, A CORPORATION OF ALABAMA.

FUEL PUMP.

Application filed April 18, 1923. Serial No. 633,037.

To all whom it may concern:

Be it known that I, JOHN ERLE DOUGLAS, citizen of the United States, residing at Birmingham, in the county of Jefferson and State of Alabama, have invented certain new and useful Improvements in Fuel Pumps, of which the following is a specification.

The present invention relates to improvements in injection pumps for use particularly with Diesel or the like internal combustion crude oil engines, and the invention has for an object to secure the injection of the fuel at constant pressure irrespective of the load upon the motor and to obtain a spraying of the fuel at the fuel nozzle at greatly increased pressure resulting in the more perfect atomization at all speeds.

Another object of the invention lies in providing an improved injection pump in which the moving parts will be lubricated by the fuel oil under pressure, the pump being so packed as to avoid the leakage of fuel even at high pressure.

A further object of the invention is to provide an improved injection pump actuated continuously during the running of the motor and operating to draw from the fuel tank and circulate the fuel at all times, there being an automatic control device associated with the pump and with the engine governor for determining the amount of fuel to be delivered to the nozzle in the cylinder head and permitting the excess of pumped fuel to be circulated back to the fuel tank.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view of a crude oil engine having the improved pump and associated parts constructed and operating according to the present invention.

Figure 2 is an enlarged longitudinal section taken through the pump.

Figure 3 is an enlarged fragmentary side view, with parts shown in section showing the pump and adjacent parts.

Figure 4 is a similar view taken from the opposite side of the pump, and

Figure 5 is an end view of the pump and its allied mechanism.

Referring more particularly to the drawings, 1 designates in general an internal combustion crude or heavy oil engine of the Diesel or other type in which 2 is the crank shaft and 3 the cylinder. The fuel tank is indicated by the line 4 and is in connection with a fuel outlet pipe 5 leading to the pump casing 6 and a fuel return or overflow pipe 7 which also communicates with the pump casing. From the pump casing the fuel previously lifted through the pipe 5 is forced into the delivery pipe 8 by which it is conveyed to the nozzle which sprays it into the combustion chamber in the head of the cylinder 3. The general operation of an engine of this character is well known and such engines are usually equipped with governors of the centrifugal type in which 10 designates the centrifugal balls carried by the outwardly movable arms 11 secured to the vertically movable ring 12 which is adapted to raise and lower the shaft 13 in accordance with the speed of the engine, the governor being driven from the crank shaft 2 for instance by a belt 14 or other associated mechanical transmission.

The improved pump is constructed more particularly as illustrated in Figure 2 in which the casing 6 is shown to contain two superimposed and longitudinally extending cylinders 15 and 16, the lower cylinder being preferably situated close to the base of the casing while the upper cylinder is situated approximately midway the height of the same or slightly above the center line. In the cylinders are plungers 17 and 18 cut away at their rear ends and provided with rack teeth 19 and 20 disposed mutually toward one another in order to be engaged alike by the teeth upon a vibrating pinion 20' carried upon a shaft 21 transversely journaled through the casing between the two cylinders 15 and 16. The rack teeth 19 and 20 are disposed substantially coincident with the axis of the plungers 17 and 18 in order to insure that the thrust developed by the movement of the pinion be transmitted centrally and equally to avoid jamming of the plungers in the cylinders or undue friction upon the walls thereof and as a consequence to minimize wear and facilitate the free action of the pump. At

one end of the block or casing 6 are plugs 22 and 23 screwed into the ends of the cylinders to enable access to be had thereto for the purpose of cleaning or removing the 5 plungers.

The pipe 5 conveying oil from the oil tank 4 is connected to the pipe section 24 projecting from the lower forward portion 10 of the pump casing 6, in which pipe section 15 is a seat for the downwardly seating check valve 25 having the perforated guard plate 26 there above communicating directly with the open end of the lower cylinder 15. A vertically disposed threaded opening 27 is 20 made in the pump casing or block to receive the pipe section 24 and also a threaded block 28 containing also a similarly downwardly seating check valve 29 communicating at its under side with the open end of the lower 25 cylinder 15. This block likewise is associated with a perforated guard plate 30 for the valve which allows the oil to be pumped upwardly into a transverse passage 31 leading to the open adjacent end of the upper 30 pump cylinder 16 and to the pipe 8 which delivers the fuel to the nozzle, the pipe being provided with a screw threaded connection 32 by which it is secured in fluid type fashion to the casing. A valve seat 33 for a valve 34 is secured above the intermediate portion of the passage 31 and in a recess 35 made substantially coaxial with the lower threaded opening 27, this recess 35 communicating at its upper end 36 with the pipe 7 for returning fuel to the tank 4. The check valve seats downwardly also and is normally held closed by a rotary stop 37 carried upon a shaft 38 transversely journaled through the casing and projecting at 40 one end as for instance as seen in Figure 4 where it receives an arm 39 having a spring 40 engaged with its lower end in tending to urge the arm in a counterclockwise direction to hold the stop 37 normally against the 45 check valve 31. The spring 40 is preferably a relatively strong spring to withstand the pressure developed in the pump.

The arm 39 also projects above the shaft 38 to which it is fixed and is pivotally coupled to a link 41 having at its free end a yoke 42 occupied by a tapering or wedge shaped bar 43 depending from the governor shaft 13 and pivoted thereto as indicated at 44 in Figures 1 and 5 in order that the bar 55 43 may swing in the same direction with the link 41 and in the direction of the slot in the yoke which also contains a finger 45 projecting upwardly from a rock shaft 46 extending transversely through the casing 60 and having a continuous oscillating movement imparted by the moving parts of the engine. The finger 45 is so disposed that it bears against one wedge-shaped side face of the bar 43, while the bar engages against 65 the end of the yoke. A coil spring 47 is

looped about the yoke and a stud 48 secured to the pump block 6 and a like stud 49 may be provided to hold one end of the spring 40.

One mechanism for securing the reciprocation of the pump plungers and also the oscillation of the rock shaft 46 is illustrated in Figures 1 and 3 in which an eccentric 50 upon the crank shaft 2 is utilized to move the eccentric strap 51 and also this eccentric 55 strap the arm 52 secured thereto and lying along one side of the pump casing 6. At its free end this arm 52 is slotted as indicated at 53 receiving therein a pin 54 which projects from an arm 55 upstanding from the pump shaft 21 upon which the pump pinion is mounted. Upon this same shaft 21 is an eccentric 55 having a strap secured to an arm 56 which is pivotally coupled as indicated at 57 to a depending arm 58 upon the rock shaft 46.

In operation, as the engine shaft 2 rotates it will revolve the governor balls 10 and also reciprocate the rod 52 by which an oscillating movement is communicated through the arm 55 and shaft 21 to the pinion 20. Due to the gear connection between the pinion and the plungers 17 and 18, the latter will be reciprocated in the cylinders 15 and 16 but the plungers will move in constantly relatively reverse directions. When for instance the lower plunger 17 is moving to the right in Figure 2, the upper plunger 18 is moving to the left. The plunger 17 in thus moving to the right lifts the check valve 25 and draws in a supply of fuel oil from the tank through the pipe 5. On the next subsequent movement to the left, the plunger 17 displaces this supply of fuel and forces it upwardly past the check valve 25 to the upper cylinder 16 which is offering a constantly enlarging chamber because of the receding of the upper plunger 18. Upon the next stroke of the upper plunger, the check valve 29 is closed and the upper check valve 34 being held against its seat by the stop 37, the fuel oil will be forced into the pipe 8 and conveyed to the nozzle end where it is sprayed into the combustion chamber of the motor. Any excess of oil is returned to the fuel tank by way of the pipe 7 whenever the check valve 34 is permitted to open, as when the stop 37 is withdrawn. This function is accomplished by the action of the governor in combination with the wedge bar 43 and the finger 45. The finger 45 is constantly oscillated together with the shaft 21 and the finger striking the bar 43 which rests against the link 41 serves to turn through the fraction of a rotation the shaft 38. This recurs during each cycle of the engine and the timing of the removal of the stop 37 from the check valve 34 is arranged by the position of the inclined edge or edges 130

of the bar 43 with respect to the link 41 and the finger 45. As the engine speed increases the governor balls 10 fly out and lower the shaft 13 and with it the bar 43 so that the wider portion of the latter is presented to the finger 45 which will thereupon strike the bar earlier and cause an earlier movement of the trip. The oil will thus be enabled to escape back to the tank and at high speeds a lesser amount of oil is thus furnished to the combustion chamber and the governor will consequently restrict the speed of the engine within a predetermined maximum. As the engine speed decreases the bar 43 will be lifted so that its lower tapered edge will recede further away from the finger 45 and the stop 37 will be opened only at a later period.

It will be appreciated that with the double plunger pump of the character described, the stress will devolve not only upon the plungers, but also upon the actuating gear because of the oil pressure upon both pistons and the oil will further serve to lubricate the pistons, the casing or block of the pump being made fluid tight wherever joints or shaft bearings are mounted therein.

It will further be appreciated that the position of the eccentric on the main shaft controls the time of injection while the speed of the engine through the governor controls the amount of injection or in other words the governor does not control the timing of injection as is done in the case of present engines of this type.

It is also to be noted that excessive pressure in front of the upper plunger resulting from the stoppage of the nozzle will open the relief valve 34 by overcoming the spring pressure and this movement is allowed by the slotted yoke 42.

It is obvious that various changes and modifications may be made in the details of construction and design of the above specifically described embodiment of this invention without departing from the spirit thereof, such changes and modifications being restricted only by the scope of the following claims:

50. What is claimed is:

1. A fuel pump for internal combustion engines comprising an initial pump arranged in connection with a source of fuel supply, a final pump in communication with the initial pump, a check valve between the pumps opening toward the final pump, said final pump having a relief port in communication with the source of supply, a relief valve normally closing said relief port, positive stop means engaging said relief valve to hold the same closed during the major period of the cycle of operations of the engine, means driven by the engine for periodically removing said positive stop means from engagement with said relief

valve, means for varying the time and duration of the removal of said stop means from the valve with reference to each cycle of operations of the engine, and means whereby said final pump is placed in communication with the fuel nozzle of the engine. 70

2. A fuel pump for internal combustion engines comprising a casing having initial and final pump chambers with a passage connecting the ends of the chambers, a check valve in said passage opening away from the initial pump chamber, said initial pump chamber being in connection with a source of fuel supply, said final pump chamber being in connection with the fuel nozzle of the engine, pistons fitted to reciprocate in said chambers, a common means for alternately reciprocating said pistons from movement derived from the engine, said casing having a relief port in connection with the final pump chamber, a relief valve normally closing said port, a rotary stop adapted to positively engage said relief valve to hold the same closed, positive means driven by the engine for acting to shift said rotary stop away from the valve, and means whereby the period at which said stop is shifted and the duration of time the stop is held away from said valve may be varied directly in proportion to the speed of the engine. 85

3. In combination with an internal combustion engine and a governor therefor, of a fuel pump comprising an initial pump in communication with a source of fuel supply, a final pump in connection with the initial pump and with the fuel nozzle of the engine, a check valve between the pumps opening toward the final pump, a relief port in connection with the final pump, a relief valve normally closing said relief port, a rotary stop adapted to positively engage said relief valve to hold same seated, a slotted link connected to said rotary stop, an oscillating finger moved by the engine engaging in said slotted link, and a wedge connected for variable movement to said governor and projecting between the slotted link and the finger for varying the time period and duration of the opening of the relief valve during each cycle of operations in terms of the speed of the engine. 105

4. In combination with an internal combustion engine and a governor therefor, a fuel pump comprising an initial pump in connection with a source of fuel supply, a final pump in connection with the engine and with the initial pump, a check valve between the pumps closing toward said initial pump, a relief valve for the final pump, a rotary stop positively engaging said relief valve, strong resilient means for normally holding said rotary stop against the valve, a link connected to said stop, a vibrating finger moved by the engine, and 120

125

130

- a wedge shiftable with the governor and disposed between said finger and the link for changing the timing and duration of the opening of the relief valve.
5. In combination with an internal combustion engine, and a governor therefor, a fuel pump comprising initial and final pumps having communication, a check valve between the pumps opening toward the final pump, said initial pump being in connection with a source of fuel supply, said final pump being in connection with the engine and with the source of fuel supply, a normally closed relief valve for preventing the pumping of the fuel back to the supply from the final pump, a rotary stop normally engaging and closing said relief valve, relatively strong resilient means acting to hold said stop in closed position, a link connected to said stop, a vibrating finger, a wedge carried by the governor and moving variably
- between said finger and the link, and an eccentric motion for the vibrating finger derived from the movement of the engine.
6. A fuel pump comprising means for drawing in and ejecting a supply of fuel, a relief valve in the pump, a stop associated with the relief valve, means for normally and yieldably holding the stop and valve in closed position, a slotted arm connected with said stop, a vibrating finger operating in the slotted yoke and driven continuously by movement derived from the engine and for moving the yoke to remove the stop from the relief valve once during each cycle of operation of the engine, and a wedge adjustably carried by the governor and adapted to fit between the slotted arm and said vibrating finger for varying the time period at whatever finger will open the stop and retain the stop opened.

JOHN ERLE DOUGLAS.
